Attorneys

UNITED STATES PATENT OFFICE.

PERHAM F. HEARSCH, OF SEATTLE, WASHINGTON.

EASY CHAIR.

Application filed April 2, 1923. Serial No. 629,246.

To all whom it may concern:

Be it known that I, PERHAM F. HEARSCH, a citizen of the United States of America, and resident of the city of Seattle, in the 5 county of King and State of Washington, have invented certain new and useful Improvements in Easy Chairs, of which the following is a specification.

My invention relates to easy chairs and 10 consists of a chair in which the seat and back are pivoted to swing about a pivot located towards the forward edge of the seat, and in which said seat and back are spring supported so as to normally have a relative- 15 ly small angle of swing under the weight of a person of average weight, and which is, however, provided with means so that an increased angle of inclination can be given the seat and back by the positive application 20 of power thereto through a member engaged by the foot, whereby the chair may be permanently locked in such increased angle of inclination when desired.

The object of my invention is to provide 25 a chair having a pivoted back and seat, with means of simple character whereby the swinging of the chair through an increased angle may be conveniently done where the weight of the person is not alone sufficient 30 to cause this increased swing.

The features of my invention which I believe to be new will be hereinafter described and then particularly defined in the claims.

35 The accompanying drawings show the type of construction which I now prefer to use in carrying out my invention.

Figure 1 is a side view of the chair showing the face of the base which is towards 40 the observer as being removed so as to show the mechanism for operating the chair.

Figure 2 is a similar view showing the chair in its inclined position.

The chair is provided with a base as 1, 45 which is or may be of any suitable type of construction, and a seat and back, 2 and 20, which it is designed shall be of such integral construction that there is no relative movement between these parts. The seat 50 and back are pivoted to swing about a pivot axis represented at 12. Under the rear edge of the seat, springs as 3 are shown which are supported at their lower edge upon a bar or bracket as 30 carried by the base 55 and engaging the rearmost part of the seat. These springs are designed to be sufficient in

number and in strength to support a person of at least average weight without being depressed too much for comfort. It is, however, designed that the chair be capable of 60 swinging backward and downward somewhat more than would ordinarily be desired, as when a person desires to recline in position of rest. I have provided means whereby the seat and back may be swung to 65 an angle which is greater than that which follows from the weight of the occupant, whenever such increased angle is desired. This mechanism is one which is positively operated by engagement of the foot of the 70 occupant.

Pivotedly carried upon the chair base is a bell crank lever or levers 4. One of these may be mounted at each side of the chair. One arm of this lever is connected with the 75 seat by means of a link as 5, which link is also pivotally connected with the seat base as at 51. The connection between the bell crank lever and the link or the connection between the link and the seat, should be of 80 such character that the seat may be depressed as much as would ordinarily occur by the weight of the occupant, without requiring any movement of the bell crank lever. This is shown as accomplished by 85 having the pin 52 carried by the lever, passing through a slot 50 in the link so that downward movement of the link will not cause any swinging action of the lever until it has passed through a considerable distance. At the same time, if power be applied to the lever to swing it, it will positively transmit this power to the seat. 90

To the other arm of the lever 4 is connected 95 a bar 6 which bar is provided with notches as 60 making a ratchet bar of it, and these are engaged by a pawl 61 pivoted upon the sides of the base. This pawl has a rod as 62 connected therewith and extending up at the side of the chair where it may be 100 conveniently engaged by the occupant. By lifting this rod 62 the pawl is disengaged from the ratchet bar 6.

A guide for this ratchet bar is provided, 105 preferably close to the forward edge of the base. This is shown as consisting of a plate 7 which has its ends secured to the side of the base and is centrally bowed out sufficient to pass the ratchet bar 6. Beneath this plate 7 is preferably mounted a small roller 70 110 whereby the friction of the bar 6 in passing through the guides is reduced.

Secured to the forward or outer end of the ratchet bar 6 is a board 8. This is pivoted as at 80 so that it may swing up into the position shown in Figure 1 or downward into 5 the position shown in Figure 2. Normally this board would be up or in the position shown in Figure 1. The ordinary use of the chair would produce no movement upon the ratchet bar 6 and the board 8 would remain 10 in its closed position. If at any time the weight of the occupant of the chair will not depress it as far as may be desired, the board 8 may be swung down into the position shown in Figure 2, and the foot or shoe 15 of the occupant may be engaged by a cross bar 81 which is carried by the said board in somewhat raised position. By pushing outwardly upon this, power may be applied to the seat through the ratchet bar 6, bell crank 20 lever 4 and link 5, so as to additionally depress the springs 3 and secure a farther backward and downward swing to the back and seat.

What I claim as my invention is:

25 1. A chair having a back and seat swinging about an axis located near the front edge

of the seat, springs holding the seat raised, a rod mounted in the base for reciprocation from front to rear, means connecting said rod with the seat to lower it, and a board 30 pivoted upon said rod to normally form a section of the front of the chair base, said board having upon its inner face a raised bar adapted when the board is swung down to be engaged by the feet to thereby pull 35 down the seat.

2. A chair having a base, a seat hinged near its front edge, seat supporting springs beneath the rear edge of the seat, a bell crank lever pivoted upon the base, a link connect- 40 ing an arm of said lever with the seat and having a sliding connection permitting free downward movement of the seat, a ratchet bar connecting with the other arm of the lever, a holding dog, and a member carried 45 by said bar and engageable by the foot for drawing out said bar to thereby pull down the seat.

Signed at Seattle, King County, Washington, this 24th day of March 1923.

PERHAM F. HEARSCH.
